(57) **CLAIM**

The ornamental design for a garden composter assembly, as shown and described.

DESCRIPTION

FIG. 1 shows a perspective view of the new garden composter (container and support frame and moving hand truck). FIG. 2 shows a perspective view of the container of the new garden composter without an ending closure cap and with the middle door closed.

FIG. 3 shows a perspective view of the container of new garden composter with the middle door opened and the ending closure cap closed.

FIG. 4 shows a perspective view of the container of new garden composter from other side; and,

FIG. 5 shows a perspective view of the support frame and moving hand truck.
